C. GEBHARD,
WINDOW OPERATING MECHANISM,
APPLICATION FILED AUG. 12, 1920.

1,387,432.

Patented Aug. 9, 1921.

UNITED STATES PATENT OFFICE.

CONRAD GEBHARD, OF MUNICH, GERMANY, ASSIGNOR TO "ASFAG" AKTIENGESELLSCHAFT, OF GLARUS, SWITZERLAND.

WINDOW-OPERATING MECHANISM.

1,387,432.

Specification of Letters Patent.

Patented Aug. 9, 1921.

Application filed August 12, 1920. Serial No. 403,161.

To all whom it may concern:

Be it known that I, CONRAD GEBHARD, a citizen of the Republic of Germany, residing at Munich, Tegernseerlandstrasse 135, 5 Germany, have invented certain new and useful Improvements in Window-Operating Mechanism, for which I have filed applications, in Germany, Nov. 4, 1918; in Switzerland, July 9, 1920, appln. No. 7069; in France, July 22, 1920, appln. No. 131,574; in Belgium, July 16, 1920, appln. No. 231,755; in Italy, July 10, 1920, appln. No. 292/284; in Spain, July 14, 1920, appln. No. 74,964; in England, Aug. 3, 1920, appln. No. 22936/20; 15 and I do hereby declare the following to be a clear, full, and exact description of the invention, such as will enable others skilled in the art to which it appertains to make and use the same, reference being had to the 20 accompanying drawing, and to letters or figures of reference marked thereon, which form a part of this specification.

The invention relates to improvements in a device for fixing and actuating sliding windows particularly on vehicles, wherein, 25 in a known manner, by means of a folding lever which is rigidly connected to its axle of rotation the linkage for actuating the windows can be displaced as well as the lateral rods can be shifted.

The known sliding windows of this type provided with such a device are either fitted with special upper and lower frames which have to be disengaged first by the lateral rods in order to be able to shift the window, 35 or the sliding windows are provided with a special upper guidance, which secures the window in the top-most position.

Besides the high costs these sliding windows present the disadvantage that their 40 construction is very complicated on account of these special pressure frames and further they are subjected to jamming and to getting out of order. The sliding windows with upper guidance cannot be applied to 45 vehicles with folding hoods and can only be displaced when mounted in a vertical position and not in a more or less oblique position.

The object of the present invention is to 50 improve the known constructions so that the hitherto existing disadvantages of these sliding windows are overcome in dispensing with the separate pressure frames and with 55 the upper guidance and yet enabling a re-

liable fixing and a simple and easy shifting of the window, while securing it against any motion by its own weight.

According to the invention, the above mentioned features are attained by connecting a crank, which is rigidly fixed to the axle of the actuating mechanism, with its one end in an articulated manner to a lever that can be folded so that when said lever is folded a sliding member with a beveled end 60 is pulled along a slot provided in the axle, whereby a bushing being displaceably arranged surrounding the axle and provided on its outside with a lug in the shape of an inverted V is pushed against the action of a 65 compression spring toward the outside, upon which displacing motion said lug co-acts with two members turnably mounted on two pivots pressing them apart and simultaneously causing the lateral rods with their 70 beveled ends to be pressed against the clamping members that co-act with the window so that the window is fixed in position, while on the other hand when the lever is unfolded the sliding member is displaced relatively to 75 the slot in the axle and the bushing glides toward the inner side upon the action of the spring, the lug is withdrawn from said members whereupon the latter are again closed by the lateral rods which are influenced by 80 springs so that the window may be moved up or down as the clamping jaws disengage 85 the latter.

The accompanying drawing shows in a diagrammatic manner an exemplification of 90 the invention in which:

Figure 1 is a window arranged in the door of a vehicle and seen from the inside; Fig. 2 is a vertical section of Fig. 1, some parts being omitted;

Fig. 3 is a plan view of Fig. 1;

Fig. 4 shows on a larger scale part of the actuating mechanism in front view the cover plate being removed;

Fig. 5 is a section through Fig. 4, with the 100 lever unfolded;

Fig. 6 illustrates a plan view of Fig. 4 with the lever in its folded position.

a denotes the door inside the frame of which the window b slides in recesses c. In 105 the upper part of these recesses beveled clamping members d are mounted yielding.

The shifting of the window is carried out by turning the handle e the axle f of which 110

transmits the turning motion to a disk *g* rigidly connected to it. This disk acts as a crank for the connecting link *h* and its turning motion is limited by the stops 4 and 5 which abut against the connecting link and prevent too great a turning motion of the system. The motion is transmitted by the connecting link *h* to a pivoted lever *i*, which is turned in the direction of the arrow shown 10 in Fig. 1 and which displaces the bell crank lever *l* by means of the link *k*. To the lower end of the bell crank lever *l* a roller *m* is provided which rolls along guides *n* fitted to a frame in the lower part of the 15 window. In consequence of the pressure exerted by the lever *l* the window *b* is shifted upward or downward according to the direction in which the handle is turned. In order to damp the downward movement of 20 the window a spring loaded buffer rod *o* is interposed between the lever *i* and the lower edge *a* of the door frame. When the lever *i* moves downward the spring is compressed and takes up any eventual shocks so that 25 the window *b* can never fall against the frame even if the handle is let go.

The fixing of the window *b* in any desired position is carried out by means of the handle *e* and a pair of lateral rods *v* operatively connected to it. For this purpose the handle *e* consists of a lower part 2 rigidly connected to the axle *f* and the upper part 3 articulated to the lower part and adapted to be folded on to it, in this way the 30 handle part is lengthened into a lever and the whole mechanism may be worked very easily. The axle *f* is surrounded by a bushing *p* which is provided at one side with a lug *q* that has the shape of an inverted V, 35 the bushing being pressed toward the outer side, (i. e. toward the handle *e*) by means of a spring *r*. The axle *f* is provided with a slot in which a sliding member *s* fitted with an enlarged end slides. The sliding member *s* has a vertical slot 6 provided at one 40 end into which a gliding pivot *z* of the upper part of the handle is inserted. To the inner side of the wall of the door which carries the whole device and toward the window *b* the members *t* are rotatably mounted 45 around pivots *y*. Against these members *t* the rods *v* abut, which rods are pressed against the latter by the plate springs *w*, the rods *v* are fitted with beveled ends *x* which 50 co-act with the beveled clamping parts *d*. The described device is operated as follows: If the upper part 3 of the handle *e* is folded on to the lower part 2 the sliding member *s* together with its enlarged end is 55 pulled through the slot of the axle *f* so far that the bushing *p* is pushed toward the outside overcoming thereby the pressure of the spring *r* and the lug *q* presses apart the two members *t* turning them around the pivots *y*. 60 The members *t* push the rods *v* against the

pressure of the springs *w* in an outward direction. The wedge shaped ends *x* of the rods *v* press the beveled clamping members *d* toward the window in such a way that the latter is held firmly in any given height or 70 position.

In order to shift the window the upper part 3 of the handle *e* is unfolded, whereby the sliding member *s* with its enlarged end is pushed along the slot of the axle *f* and the bush *p* glides through the action of the pressure of the spring *r* toward the inner side, the lug *q* disengages the members *t* whereupon they are pushed against each other by the action of the plate springs *w* 75 and the interposed rods *v*. The wedge-shaped ends *x* of the rods *v* disengage the beveled clamping members *d*. The latter are, through the action of the springs *w*, removed from the window and disengage 80 the latter so that the window can at will be raised or lowered by turning the handle part. 85

In order to fix the window again the upper part 3 of the handle *e* has only to be folded. 90 The frame of the window is provided at its right and left hand side with extended parts 1 which insure a reliable fixing of the window and an effective guidance when it is raised by its full height. 95

This construction insures a safe working of the mechanism without any shocks occurring and a perfectly safe fixing of the window in any desired position. The latter is effectively guided up to its highest position and no upper guidance is required, so that for instance a vehicle without a cover can be closed in around its whole circumference by such windows without materially hindering the view. This construction enables further to use such a window with open vehicles fitted with half doors. No straps, ropes, wires, cords, toothed wheels or other means to wear out quickly are utilized. The displacement of the window is 100 easy, simple and requires no special exertion of strength. Any jamming or clattering of the window is excluded and the latter moves in a gentle way when being shifted. 110

I claim:

1. A device for fixing and actuating sliding windows, comprising a window adapted to slide in recesses of a frame, a folding lever rigidly fixed to a turnably mounted axle, a plurality of levers linked to each other and operatively connected to said folding lever and to the window so that upon a turning of said folding lever in one of the two directions of rotation the window is raised and lowered respectively, lateral rods operatively 120 connected to clamping members provided in the recesses in which the window glides whereby a pressure of said rods causes the clamping members to be pressed against the window and fix the latter in any given ele- 125 130

vation, and an operative connection between said folding lever and the lateral rods so that upon a folding of the lever said rods are caused to actuate said clamping members.

2. A device for fixing and actuating sliding windows, comprising a window adapted to slide in recesses of a frame, a folding lever rigidly fixed to a turnably mounted axle, a plurality of levers linked to each other and operatively connected to said folding lever and to the window so that upon a turning of said folding lever in one direction the window is raised and upon a turning in the other direction the window is lowered, a slot provided in said axle, a gliding member fitted with an enlarged end operatively connected to the folding lever and adapted to be displaced in said slot upon the folding of the lever, a spring loaded bush surrounding said axle and arranged displaceably in an axial direction by the enlarged end of said gliding member engaging said bush, a lug of an inverted V shape provided on the outside of said bush, two members rotatably mounted on pivots and pressed apart from each other by said lug, lateral rods abutting against said members and fitted with beveled faces at their other ends, spring loaded clamping members provided in the recesses in which the window slides, said members being provided with beveled faces which co-act with the beveled

ends of said lateral rods so that upon a pressure of said rods the clamping members are pressed against the window and fixing it securely in the recesses at any given height.

3. A device for fixing and actuating sliding windows, comprising a frame having recesses, a window to slide in said frame and recesses, an axle, a handle secured to the axle, a disk on said axle, a rod pivoted to said disk, a lever pivoted to said frame, a bell-crank lever pivoted to the frame and connected to the first mentioned lever, said bell-crank lever having means at its end to engage under the window.

4. A device for fixing and actuating sliding windows, comprising a frame having recesses, a window to slide in said frame and recesses, an axle, a handle comprising a lower part connected to said axle and an upper part pivoted to said lower part, a window raising and lowering mechanism operated from said axle, wedging devices engaging in said recesses between the frame and window, a slot in said axle, a cam element slidable in said slot and pivoted to said upper handle part, and mechanism operated by said element to actuate said wedging devices.

In testimony that I claim the foregoing as my invention, I have signed my name.

CONRAD GEBHARD.
